COMBINED OBSERVATION AND TALKING WICKET

Clayton P. Nielsen, Los Angeles, Calif.

Application December 27, 1955, Serial No. 39,471

Term of patent 14 years

(Cl. D13—1)

Figure 1 is a front perspective view of a combined observation and talking wicket showing my new design.

Figure 2 is a rear perspective view.

Figure 3 is a rear perspective view with the door in a partially open position; and

Figure 4 is a side view thereof.

I claim:

The ornamental design for a combined observation and talking wicket, substantially as shown.
